1931

UNITED STATES PATENT OFFICE.

MINNIE B. KENT, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 18,060, dated February 14, 1888.

Application filed January 11, 1888. Serial No. 260,450. Term of patent 3½ years.

To all whom it may concern:

Be it known that I, MINNIE B. KENT, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by the pattern will appear.

The design shows a close-fitting basque and a round walking-skirt. The skirt displays a kilted panel on the right-side gore, a long front drapery falling in wide kilt plaits at the left side to the edge and exhibiting draping plaits at the belt and jabot folds at the right-side edge, toward which the lower outline is rounding; a full-back drapery that falls in

jabot folds at the left side, where it is quite short, and in free folds at the right side, and exhibits draping plaits at the belt. The basque displays close-fitting fronts flaring toward the shoulders over a V-shaped vest in bréton style, a close-fitting back falling in two square tabs between points described by the side backs, coat-sleeves, and a standing collar.

What I claim as my invention, and desire to secure by Letters Patent, is—

The design for a miss's costume, as shown in the engraved prints accompanying this specification.

MINNIE B. KENT.
